Primary Examiner — Richard Kearney*Assistant Examiner* — Christina M. Dodson(74) *Attorney, Agent, or Firm* — Stetina Brunda Garred & Brucker(57) **CLAIM**

The ornamental design for a vehicle light system remote controller, as shown and described.

DESCRIPTION

FIG. 1 is a front perspective view showing a vehicle light system remote controller of the present invention;

FIG. 2 is a rear perspective view thereof;

FIG. 3 is a top view thereof;

FIG. 4 is a front view thereof;

FIG. 5 is a bottom view thereof;

FIG. 6 is a rear view thereof;

FIG. 7 is a left side view thereof; and,

FIG. 8 is a right side view thereof.

In the drawings, the broken line showings are for the purpose of illustrating portions of the vehicle light system remote controller or environmental structure that form no part of the claimed design.
